UNITED STATES PATENT OFFICE.

JOHN H. GOODFELLOW, OF LOWELL, MASSACHUSETTS, ASSIGNOR TO THE LAMSON CONSOLIDATED STORE SERVICE COMPANY, OF NEW JERSEY.

STORE-SERVICE APPARATUS.

SPECIFICATION forming part of Letters Patent No. 608,594, dated August 9, 1898.

Application filed May 12, 1896. Serial No. 591,307. (No model.)

To all whom it may concern:

Be it known that I, JOHN H. GOODFELLOW, of Lowell, in the county of Middlesex and State of Massachusetts, have invented a new and 5 useful Improvement in Store-Service Apparatus, of which the following, taken in connection with the accompanying drawings, is a specification.

This invention relates to improvements in 10 that class of store-service apparatus in which the carrier engages with a way and a propelling-wire and is moved by the separation of the same. It relates more particularly to the mechanism for spreading the way and the 15 propelling-wire. It has for its object the provision of a mechanism that is simple in construction, easy of operation, and efficient in its purpose.

The invention consists in the novel construction, combination, and arrangement of parts, such as will be hereinafter fully described, pointed out in the appended claims, and illustrated in the accompanying drawings.

25 In the accompanying drawings, in which similar letters of reference designate corresponding parts, Figure 1 is a side elevation of a device embodying the invention. Fig. 2 is a front elevation of the same.

30 Referring to the drawings, A designates the way or track on which the carrier travels. It is secured at one end to the foot b of the standard B, and at the other end it is secured in any manner suitable in the premises. 35 From the foot b project the arms b', having sockets b² formed in their outer ends.

Guide-rods C are seated at their lower ends in the sockets b² and are secured at their upper ends in the bracket D. The latter has 40 arms d, with openings d' formed in their outer ends through which the guide-rods pass. It is to be observed that the guide-rods are inclined at their upper ends toward the direction from which the way approaches.

45 A separating-block E is mounted on the guide-rods C and is movable thereon. From its upper end a recessed ear e' extends, and from its lower end an apertured lug e² projects. To the apertured lug is secured an 50 end of the propelling-wire F. In its normal position the wire is substantially parallel with

the way and in close proximity thereto. Its other end is secured in any suitable manner. Intermediate of the ear e' and the lug e² an engaging spring G is secured to the separating-block. 55

A coupling mechanism is mounted on the guide-rods C above the separating-block. It consists of the latch-body H, movably mounted on the guide-rods, and the latch h, pivoted 60 to the face of the body. The latch has a hooked end projecting below the body adapted to engage with the recessed ear e' of the separating-block. A leaf-spring h' is secured to the body and bears on the said hooked end 65 of the latch to normally hold the same in an engaging position. The other end of the latch extends above the body in a position to be struck by the trip h², adjustably mounted on the guide-rods, when the body is moved up- 70

ward. Projecting from the rear of the latch-body is the lug h³, having a socket formed therein. A cord I, with a knotted end seated in the said socket, leads through an opening in the foot b and has attached to its free end 75 the handle i.

A spring mechanism normally holds the latch-body in an elevated position on the guide-rods. It consists of an elastic cord J, looped under the lug h³ and secured at its 80 ends in the outer ends of the arms j' of the bracket j², adjustably mounted on the standard B near the upper end of the latter.

A carrier K is mounted on the way A and the propelling-wire F. It consists, essentially, 85 of the casing k, the wheels k', journaled between the sides of the casing, and the receiver k², secured to the casing. The wheels are arranged in pairs one above the other and above and below the way and the propelling- 90 wire.

The operation of the device is as follows: Assuming the parts to be in the relative positions shown in Fig. 1, the operator by means of the cord I draws the latch-body H downward against the action of the spring J until the spring-pressed latch h engages with the ear e' of the separating-block E. After the latch-body and separating-block are coupled the operator releases the cord, and the spring 95 J, retracting, moves the coupled latch-body and the separating-block to the upper ends of 100

- the guide-rods C. In its upward movement the separating-block carries with it the propelling-wire, and thereby progressively separates the latter from the way. Through the action of the spring the movement of the wire is somewhat sudden, and by the spreading apart of the two members—the way and the wire—the wire bears against the upper pair of wheels k' and the way bears against the lower pair.
- 10 The progressive spreading apart of the two members back of the carrier propels the latter forward. In the upward movement of the latch-body the latch h strikes the trip h² and is thereby released from engagement with the separating-block, and the latter by reason of gravity moves downward on the guide-rods and resumes its normal position. As the trip h² is adjustable on the guide-rods C, it can be placed to act sooner or later, as circumstances may require. The adjustable bracket j³ allows the spring-cord J, attached to it, to be regulated to act with more or less force.

25 The engaging spring G acts as a buffer to stop the carrier and also serves to retain it at the end of the way, so that it cannot rebound.

The forward inclination of the guide-rods C at their upper ends prevents the stretching of the propelling-wire by making the distances between the ends of the guides and the opposite end of the wire the same, or practically so.

Having thus described my invention, what I claim, and desire to secure by Letters Patent, is—

35 1. In a store-service apparatus, the combination of a way, a propelling-wire, a carrier adapted to engage said way and said wire and to be propelled by the separation of the same, a separating-block connected with said wire, a coupling mechanism for engaging with said block, and means for moving said coupling mechanism.

2. In a store-service apparatus, the combination of a way, a propelling-wire, a carrier adapted to engage said way and said wire and to be propelled by the separation of the same, a separating-block connected with said wire, a spring-pressed coupling mechanism for engaging with said block, and means for moving said coupling mechanism.

3. In a store-service apparatus, the combination of a way, a propelling-wire, a carrier adapted to engage said way and said wire and to be propelled by the separation of the same, a separating-block connected with said wire, a latch-body, a latch for coupling said

body and said block, and means for moving said body.

4. In a store-service apparatus, the combination of a way, a propelling-wire, a carrier adapted to engage said way and said wire and to be propelled by the separation of the same, a separating-block connected with said wire, a sliding latch-body, a latch for coupling said body with said block, a spring normally holding said body away from said block, and means for moving said body against the action of said spring.

5. In a store-service apparatus, the combination of a way, a propelling-wire, a carrier adapted to engage said way and said wire and to be propelled by the separation of the same, a separating-block connected with said wire, a coupling mechanism for engaging with said block, means for moving said coupling mechanism into engagement with said block, and a tripping mechanism for disengaging said coupling mechanism and said block.

6. In a store-service apparatus, the combination of a way, a propelling-wire, a carrier adapted to engage said way and said wire and to be propelled by the separation of the same, a guide, a separating-block movably mounted on said guide and connected with said wire, a coupling mechanism movably mounted on said guide for engaging with said block, a spring normally holding said coupling mechanism away from said separating-block, means for moving said coupling mechanism against the action of said spring to engage with said block, and an adjustable tripping mechanism for disengaging said coupling mechanism from said block.

7. In a store-service apparatus, the combination of a way, a propelling-wire, a carrier adapted to engage said way and said wire and to be propelled by the separation of the same, a guide, a separating-block movably mounted on said guide and connected with said wire, a latch-body movably mounted on said guide, a latch carried by said body and adapted to connect the same with said block, means for moving said latch-body, and a trip adjustably mounted on said guide and adapted to operate said latch to release said block.

In testimony whereof I have signed my name to this specification, in the presence of two subscribing witnesses, on this 4th day of May, A. D. 1896.

JOHN H. GOODFELLOW.
